VALVE CORE, CONTAINER, AND STEM

Henry Z. Gora, Bridgeport, Conn., assignor to
 Jenkins Bros., Bridgeport, Conn., a corpora-
 tion of New Jersey

Application April 3, 1937, Serial No. 134,863

10 Claims. (Cl. 277—42)

The present invention relates to valve cores, core containers and to rubber valve stems embodying the cores and containers, a principal object being to provide a capless type of stem wherein the core may be readily screwed in or out in assembly and replacement.

The standard valve core comprises a plug portion which must be threaded to position in a container. According to the present invention the usual pin of the standard core is provided with a head, spaced from the plug, which normally fills the extremity of the core container for the purpose of excluding foreign matter. The container inwardly of the normal position of the head is internally enlarged so that when, as in an inflating operation, the head is moved into the enlarged zone, air may readily pass the head. With such an arrangement the plug portion cannot be directly gripped for the purpose of screwing it completely to or from its operative position, since access to it is blocked by the head. This difficulty I overcome herein by providing means for transmitting rotative movement of the head, which is accessible, to the plug portion. One such means is shown by way of example in the accompanying drawing, in which:

Figure 1 is an elevation of a rubber valve stem incorporating the present invention;

Figure 2 is an enlarged section substantially on line 2—2 of Figure 1;

Figure 3 is a view in perspective of the core appearing in Figure 2; and

Figure 4 is a plan view of the structure of Figure 2.

Referring to the drawing, the core is shown by itself in Figure 3 and is generally designated by the reference numeral 10. In Figure 2 the core is shown in operative position in the container generally designated by the reference numeral 11.

The core, except for the addition of a head and the necessary modification of the valve pin in order to receive the head, may be of standard construction and is so shown in the drawing. It comprises a barrel 12 which at its lower extremity has an annular valve seat 13 which is surmounted by an internal annular ledge 14. Near its upper end the barrel is exteriorly annularly relieved for the purpose of receiving a packing band 15.

Surmounting the barrel 12 is a plug portion 16 which as here shown is of substantially flat form with its longitudinal edges externally threaded and is provided with a longitudinal opening which slidably receives the valve pin

17 which extends axially through the barrel 12 and projects above and below the plug and barrel.

At its lower end the pin 17 has secured thereto a cup 18 which carries a compressible washer 19 for direct cooperation with the seat 13. Strung on the pin 17 is a volute compression spring 20 whose lower end seats on the ledge 14, the upper end of the spring bearing against abutments as at 21 on the pin 17. The spring 20 thus acts to hold the movable valve body constituted by members 18 and 19 yieldably against the seat 13.

At its upper extremity pin 17 is reduced at 22 and is received in an opening in a head 23 of circular cross section.

The head 23 on its face toward plug 16 is provided with a diametrical recess or groove 24 against the top wall of which bears the shoulder which exists at the upper end portion of pin 17 by reason of the size reduction of the latter and the extremity of the pin is riveted over in a counter-sink formed at the top of the head opening so that, as here shown, the head is rigidly fixed on the pin. The top face of the head is relieved at opposite sides to produce an upstanding diametrical rib or tongue 25.

The container 11 is in the form of a tubular metal stem portion of circular cross section provided at its upper or outer extremity with a circular opening 26 of slightly greater diameter than head 23 so that when the latter is in the normal position shown in Figure 2 its full circular portion closes the opening. The clearance is preferably extremely small, that is, merely sufficient to permit free axial movement of the head in the opening upon reciprocation of the pin 17 so that proper sealing of the movable valve body will in no way be interfered with.

Below the end opening 26 the container is internally conically enlarged, at 27, downwardly and outwardly to a cylindrical enlargement 28 below which the internal walls of the container are inwardly approached at 29 and provided with threads 29' engageable by the plug portion 16. Below the threads the internal walls of the container are downwardly and inwardly tapered to provide a seat for the packing band 15.

The core and container are shown in operative relation in Figure 2, the parts being in their normal relation wherein the valve body bears against the seat 13 and the head 23 fills the opening 26. In this relation of parts reverse flow of air through the container 11 is prevented and an air pocket exists in the container cham-

ber portion between the head and the movable valve body. Foreign matter, such as dirt and water, is effectively excluded from the container.

Assuming it to be desired to replace the core, it is evident that the plug portion 16 is entirely inaccessible to a tool of any kind in view of the presence of the head 23 which blocks the upper end of the container. With the provisions herein disclosed, however, the head 23 may be depressed by a suitable tool to engage the upper part of plug 16 in the groove 24, this part of the plug and the groove constituting interengageable clutch means between the head and plug so that rotative movement imparted to the head is directly and positively transmitted to the plug. With the head and plug interengaged the latter may be readily screwed to position in the container or unscrewed therefrom, the rib 25 being readily engageable by a suitable tool so that the head can be conveniently manipulated.

The plug portion 16 is here shown as being separate from the barrel 12, but this is merely illustrative structure, it will be understood. With the illustrated core construction the threads of the plug portion 16 should preferably be engaged with the threads 29' to a longitudinal extent which is greater than the distance between the top of plug portion 16 and the top of the recess 24 so that upon unscrewing the plug portion from the normal position shown in Figure 2, the barrel 12 will be lifted from its seat due to the rise of the plug portion by reason of its unthreading movement. At the same time the distance between the bottom of head 23 and the top of the plug portion must be sufficient to permit the head to pass inwardly for adequate air passage when the usual air coupling is applied to the stem.

In some of the standard cores the plug portion and barrel are swiveled together and in others the plug portion and barrel are made as a single piece. In these cases the barrel, of course, immediately follows the plug portion as the latter is unscrewed.

Any form of interengaging means between the head and plug may be provided, the groove 24 being here shown as designed to receive any suitable upstanding portion or portions of a plug. Rib 25 is preferably at right angles to groove 24 so that the head 23 will have maximum strength.

The container or tubular metal stem portion 11 may be associated with an inflatable body such as the innertube of an automobile tire in any suitable manner, but as here shown it is incorporated, Figures 1 and 2, in lining relation to the upper portion of the through bore 30 of the elongated body portion 31 of a rubber valve stem 32.

The valve stem 32 is of flexible rubber and has a base attaching flap 33 which is preferably circular in plan. The flap is marginally tapered to a thin edge at 33a, there being a shoulder 33b at the inner boundary of the tapered portion, this shoulder bounding a circular flat portion 33c at the base of the body 31 and concentric therewith.

The body 31 is shown as being of generally tapered form from base to tip and is circular in cross section. It has a gradually tapered portion 34 rising from the flap 33 to a more abrupt inwardly and upwardly curved portion 35. The portion 35 is surmounted by a cylindrical portion 36 which joins a conical tip portion 37. As

shown in Figure 2 the external shape of the upper end of the insert 11 determines the shape of the upper portions 36 and 37 of the body 31 which in these zones has a substantially uniform thickness.

5 The insert is laterally completely rubber-covered, as here shown.

The insert 11 is preferably bonded in the rubber body by vulcanization during the molding operation and to enhance the bond may be provided with circumferential ribs or fins 11a as shown in Figure 2.

It will be understood that the application of the present invention is not limited to rubber valve stems and that when applied to rubber valve stems the container may be of any desired length. I prefer, however, to confine the length of the container in a rubber valve stem, to the tip portion of the stem since greater stem flexibility is thus secured. The insert is preferably 15 completely covered laterally by the stem material, as shown, but may project above the stem 20 material if desired.

In a metal valve stem the container 11 might be merely the upper portion of the stem.

25 I have shown by way of example a particular means whereby rotary movement of the head 23 may be transmitted to the plug portion 16. I wish to point out that the disclosed means is merely illustrative and that the invention contemplates any means whereby the plug may be 30 rotated by reason of turning force applied to the head. Furthermore, the invention is not limited necessarily to the other details shown. I do not limit myself to these matters except as 35 in the following claims.

I claim:

1. A valve core comprising a valve pin, a valve body carried by said pin at one end of the latter, a barrel portion through which said pin 40 extends, said barrel portion having at one end a seat for cooperation with said valve body, spring means normally seating said valve body, an externally threaded plug portion at the other end of said barrel, said plug portion having an opening through which said pin slidably projects, a head on the other end of said pin and spaced from said plug portion when said valve body is seated, and normally inoperative clutch means 45 rendered operative to transmit rotative movement of said head to said plug portion only when said head is moved toward said plug portion.

2. A valve core comprising a valve pin, a valve body carried by said pin at one end of the latter, a barrel portion through which said pin extends, said barrel portion having at one end a seat for cooperation with said valve body, spring means normally seating said valve body, an externally threaded plug portion at the other end of said barrel, said plug portion having an opening 50 through which said pin projects, a head on the other end of said pin and spaced from said plug portion when said valve body is seated, and normally inoperative clutch means rendered operative to transmit rotative movement of said head to said plug portion only when said head is moved toward said plug portion, said clutch means being constituted by interengageable parts of said head and said plug portion.

55 3. In combination, a tubular metal valve stem portion and a core therefor, said core comprising a plug threaded in said tubular valve stem portion and having an axial opening, a pin 60 slidably in said opening and projecting therefrom in both directions, valve provisions including a pin 65 movable valve member carried by said pin at one

70 portion and a core therefor, said core comprising a plug threaded in said tubular valve stem portion and having an axial opening, a pin 75 slidably in said opening and projecting therefrom in both directions, valve provisions including a movable valve member carried by said pin at one

end of the latter, a head on the other end of said pin and normally positioned and of such size as to substantially fill an extremity of said tubular valve stem portion, spring means normally holding said head in its normal position and maintaining said valve provisions closed, said head in its normal position being spaced from said plug portion, said tubular valve stem portion being interiorly enlarged between its extremity and said plug portion, and means for transmitting rotative movement of said head to said plug portion.

4. In combination, a tubular metal valve stem portion and a core therefor, said core comprising a plug threaded in said tubular valve stem portion and having an axial opening, a pin in said opening and projecting therefrom in both directions, valve provisions including a movable valve member carried by said pin at one end of the latter, a head on the other end of said pin and normally positioned and of such size as to substantially fill an extremity of said tubular valve stem portion, spring means normally holding said head in its normal position and maintaining said valve provisions closed, said head in its normal position being spaced from said plug portion, said tubular valve stem portion being interiorly enlarged between its extremity and said plug portion, and clutch means rendered operative to transmit rotative movement of said head to said plug when said head is moved toward said plug portion.

5. In combination, a tubular metal valve stem portion and a core therefor, said core comprising a plug threaded in said tubular valve stem portion and having an axial opening, a pin in said opening and projecting therefrom in both directions, valve provisions including a movable valve member carried by said pin at one end of the latter, a head on the other end of said pin and normally positioned and of such size as to substantially fill an extremity of said tubular valve stem portion, spring means normally holding said head in its normal position and maintaining said valve provisions closed, said head in its normal position being spaced from said plug portion, said tubular valve stem portion being interiorly enlarged between its extremity and said plug portion, and clutch means rendered operative to transmit rotative movement of said head to said plug when said head is moved toward said plug portion, said clutch means being constituted by interengageable portions of said head and said plug portion.

6. A valve stem comprising a rubber body having a through opening, a tubular metal insert bonded in said body and lining at least the outer end portion of said opening, a valve core in said insert, said core including a plug portion threaded in said insert and a reciprocable valve pin extending through said plug portion, a head on said pin and normally filling the tip end of said insert, said insert being internally enlarged inwardly of the normal position of said head, and means for transmitting rotative movement of said head to said plug portion.

7. A valve core comprising a valve pin, a valve body carried by said pin at one end of the latter, a barrel portion through which said pin extends, said barrel portion having at one end a seat for cooperation with said valve body, spring means normally seating said valve body, an externally threaded plug portion at the other end of said barrel, said plug portion having an opening through which said pin slidably projects, a head

on the other end of said pin and spaced from said plug portion when said valve body is seated, said head having a groove on its underside adapted to receive an adjacent part of said plug portion only when the head and plug portion are made to approach each other whereby to transmit rotative movement of said head to said plug portion.

8. A valve core comprising a valve pin, a valve body carried by said pin at one end of the latter, a barrel portion through which said pin extends, said barrel portion having at one end a seat for cooperation with said valve body, spring means normally seating said valve body, an externally threaded plug portion at the other end of said barrel, said plug portion having an opening through which said pin slidably projects, a head on the other end of said pin and spaced from said plug portion when said valve body is seated, said head having a groove on its underside adapted to receive an adjacent part of said plug portion only when the head and plug portion are made to approach each other whereby to transmit rotative movement of said head to said plug portion, said head also having an outer transverse means by which it may be engaged to be rotated by a suitable tool, said means being at right angles to said groove.

9. In combination, a tubular metal valve stem portion and a core therefor, said core comprising a plug threaded in said tubular valve stem portion and having an axial opening, a pin slideable in said opening and projecting therefrom in both directions, valve provisions including a movable valve member carried by said pin at one end of the latter, a head on the other end of said pin and normally positioned and of such size as to substantially fill an extremity of said tubular valve stem portion, spring means normally holding said head in its normal position and maintaining said valve provisions closed, said head in its normal position being spaced from said plug portion, said tubular valve stem portion being interiorly enlarged between its extremity and said plug portion, said head having a groove adapted to receive an adjacent part of said plug portion when the head and plug portion are made to approach each other whereby to transmit rotative movement of said head to said plug portion.

10. In combination, a tubular metal valve stem portion and a core therefor, said core comprising a plug threaded in said tubular valve stem portion and having an axial opening, a pin slideable in said opening and projecting therefrom in both directions, valve provisions including a movable valve member carried by said pin at one end of the latter, a head on the other end of said pin and normally positioned and of such size as to substantially fill an extremity of said tubular valve stem portion, spring means normally holding said head in its normal position and maintaining said valve provisions closed, said head in its normal position being spaced from said plug portion, said tubular valve stem portion being interiorly enlarged between its extremity and said plug portion, said head having a groove adapted to receive an adjacent part of said plug portion when the head and plug portion are made to approach each other whereby to transmit rotative movement of said head to said plug portion, said head also having an outer transverse means by which it may be engaged to be rotated by a suitable tool.

HENRY Z. GORA.
